UNITED STATES PATENT OFFICE.

BERTRAM J. GOLDSMITH AND EMIL KOEB, OF NEW YORK, N. Y., ASSIGNEES, BY MESNE ASSIGNMENTS, TO THE ENGLISH & MERSICK COMPANY, OF NEW HAVEN, CONNECTICUT, A CORPORATION OF CONNECTICUT.

WINDOW AND DOOR CONSTRUCTION.

Application filed August 28, 1924. Serial No. 734,585.

Our invention relates to window and door constructions in which a vertically slidable window is installed, the invention being particularly adapted in its application to doors 5 of vehicles, such as closed automobiles.

The principal object of the invention is the production of a simple and compact device which may be installed as a unit in the window well of a door and which shall not 10 only contain means for raising and lowering the window but which shall also carry a check strap to limit the swing of the door on its hinges.

A further object of the invention is the 15 production of device of the character described which shall in addition contain mechanism for retaining the door in closed position.

To the above ends our invention consists 20 in the novel device and parts and combinations of parts thereof hereinafter more particularly described and then specified in the claims.

In the accompanying drawing illustrating 25 a practical embodiment of the invention:

Fig. 1 is a front elevation of a part of a vehicle door showing our invention applied thereto.

Fig. 2 is a horizontal section taken there- 30 through.

Referring in detail to the several figures of the drawing:

1 indicates the side members of a frame which may be the frame of a vehicle door, 35 while 2 and 3 indicate the stationary side walls or other parts of the vehicle adjacent said frame, one of the side members 1 being hinged to the part 2 as indicated at 4. The side members 1 are provided with suitable 40 guideways 5 in which a window 6 is vertically slidable, said window being either a framed or frameless pane as desired. Secured to the lower edge of the window is a channel 7 as illustrated.

45 8 indicates a metallic supporting plate or lock board which extends horizontally across the frame and which is fastened to both side members 1 by suitable screws as indicated. Said plate is also provided with a vertical 50 flange 9 engaging and screwed to the side of the right-hand side member 1. It is also provided with an upper inwardly projecting flange 10 and a lower inwardly projecting stiffening flange 11. The plate may con-

stitute a portion of the front wall of a window 55 well into which the window 6 is slidable, the opposite wall being indicated at 11'. The flange 10 is provided with a series of holes receiving bolts 12 which pass through a window sill or ledge 13, the ends of said bolts being 60 provided with nuts threaded thereon as shown whereby the sill is held to said flange.

14 indicates an escutcheon or bearing mounted on the plate 8 in which a rotatable shaft is mounted to one end of which is se- 65 cured a crank or handle 15 while the other end carries a pinion 16 meshing with a toothed segment 17 secured to a pivoted operating arm 18, pivoted to said plate, the outer end of the operating arm 18 being provided with a roller 70 19 engaging within the channel 7 on the lower edge of the window. 20 indicates a hook which is preferably pressed out of the metal of the flange 10 and to which is secured one end of a coiled spring 21, the other end being 75 secured to a suitable hook on the arm 18.

To raise or lower the window in its guide- 80 ways it is merely necessary to rotate the crank or handle 15, motion being transmitted through pinion 16, toothed segment 17, operating arm 18 and roller 19 which rides in channel 7. The spring 21 acts to counter- 85 balance the weight of the window and to assist in the raising thereof as it exerts an upward pull of the operating arm 18 on its pivot.

22 indicates a spring steel check strap, a hooked end of which engages within an eye 23 preferably punched out of the metal of the plate 8, said check strap also passing through a guide 24 also punched out of the metal of 90 the plate. The check strap is looped around and downwardly as shown, the lower portion indicated at 25 being slightly looped or curved. The other end of the check strap passes through the opening 26 in the left- 95 hand side member 1 and is non-detachably secured to a removable bracket 27 on the wall 2. This check strap limits the swing of the door on its hinges 4, as is obvious, a stop 28' being provided which is preferably punched out of the metal of the plate 8 and against which the looped portion 25 engages when the door is opened, the suddenness of the jerk on the check strap ordinarily obtaining when the door reaches its open position being thus 100 minimized.

On the right-hand side of the plate 8 we have provided a handle 28, the shank of which

is indicated at 29 and passes through suitable slots in the window sill 13 and flange 10 and is pivoted to the plate 8 as illustrated. Said shank engages a flange or projection 30 on a 5 slideable latch bolt 31, the end of which extends through openings in the right-hand side member 1 and vertical flange 9 and is adapted to enter a suitable keeper in the wall 3 to hold the door in closed position. The latch 10 bolt is normally projected forwardly into latching position by a spring 32 which is fastened to the plate 8 and to said latch bolt. To 15 retract the latch bolt to permit the door to be opened it is merely necessary to move the handle 28 against the action of spring 32 as is obvious. If so desired suitable stops 33 may be provided pressed out of the metal of the plate 8 whereby the movement of the 20 handle 28 is limited.

20 From the above explanation it will be apparent that the window actuating mechanism, handle 28 and latch bolt and associated parts as well as the check strap 22 carrying the bracket 27 are all mounted on a single 25 plate and may be shipped and installed as a unit.

What we claim as our invention is:

1. In a device of the character described, a metallic plate, a guide pressed out of the 30 metal of said plate, a stop also pressed out of the metal of said plate and a spiral metallic spring check strap extending through said guide and having an end anchored to said plate, said check strap being also adapted to 35 engage said stop to limit the movement of a door.
2. The combination with a swinging door and a stationary door-receiving structure; of a spiral metallic-spring door-check strap 40 having its looped form disposed in the plane of the said door and its opposite ends respectively secured to the same and to the said door-receiving structure.
3. The combination with a swinging door 45 and a stationary door-receiving structure; of a spiral metallic-spring door-check strap

having its looped form disposed in the plane of the said door and its opposite ends respectively secured to the same and to the said door-receiving structure; and a stop carried 50 by the said door and positioned so as to limit the straightening-out of the said spiral metallic-spring door-check strap when the said door is swung into its open position.

4. The combination with a swinging door 55 and a stationary door-receiving structure; of an assembly-plate carried by the said door; and a spiral metallic-spring door-check strap having its looped form disposed in the plane of the said door and its opposite ends respectively secured to the said assembly-plate and to the said door-receiving structure.

5. The combination with a swinging door 60 and a stationary door-receiving structure; of an assembly-plate carried by the said door; a spiral metallic-spring door-check strap having its looped form disposed in the plane of the said door and its opposite ends respectively secured to the said assembly-plate and to the said door-receiving structure; and a 65 stop carried by the said assembly-plate and positioned so as to limit the straightening-out of the said spiral metallic-spring door-check strap when the door is swung into its open position.

6. The combination with a swinging door 70 and a stationary door-receiving structure; of a spiral metallic-spring door-check strap having its opposite ends respectively secured to the said door and to the said door-receiving structure; and a stop carried by the said door and positioned within the loop of the said 75 spiral metallic-spring door-check strap in position to limit the straightening-out of the said spiral metallic-spring door-check strap when the door is swung into its open position.

Signed at New York in the county of New York and State of New York this 27th day of August, A. D. 1924.
